United States Patent Office

Des. 202,424
Patented Sept. 28, 1965

202,424

CHAIR

Robert F. Newsom, 14339 E. Garvey, Baldwin Park, Calif.

Filed Nov. 30, 1964, Ser. No. 82,835

Term of patent 14 years

(Cl. D15—1)

FIGURE 1 is a perspective view of a chair, showing my new design;

FIGURE 2 is a front elevational view thereof;

FIGURE 3 is a top view thereof; and

FIGURE 4 is a rear view thereof.

I claim:

The ornamental design for a chair, as shown.
